UNITED STATES PATENT OFFICE.

HANFORD C. JUDSON, OF NEW YORK, N. Y.

MILKING-MACHINE.

1,094,720.

Specification of Letters Patent. Patented Apr. 28, 1914.

Application filed January 17, 1914. Serial No. 812,660.

To all whom it may concern:

Be it known that I, HANFORD C. JUDSON, a citizen of the United States, residing in the borough of Manhattan, city, county, and 5 State of New York, have invented certain new and useful Improvements in Milking-Machines, of which the following is a specification.

My invention relates to a mechanical 10 milking device which is simple in construction, positive in action, and in which the parts are readily adjustable, so as to accommodate varying conditions encountered in service. My device is adapted to act by 15 the pressure of a resilient steel ribbon or spring, one end of which is fixed, the movement of the other end being limited to a rectilinear path, motion being imparted to the spring or ribbon by means of a crank 20 and pitman. Through this means acting against a fixed opposed surface, a downwardly progressive compression is obtained which simulates the operation of hand milking and closely approximates the action of 25 a calf's tongue and mouth in feeding.

In the accompanying drawings which form a part of this specification, Figure 1 is a plan view of my improved device; Fig. 2 is a perspective view of the frame 30 in which the parts are assembled; Fig. 3 is a perspective view of one of the individual box frames in which the milking mechanism is contained; Fig. 4 is a transverse sectional view on line IV—IV of Fig. 1; Fig. 5 is a transverse sectional view on line V—V of 35 Fig. 1; Fig. 6 is a similar view showing the parts in a different stage in the cycle of operations. Figs. 7 and 8 illustrate an alternative construction of the connection 40 between the compression member of a milking unit and the crank.

Referring to the drawings in detail, the numeral 1 designates the rear member of a frame provided with side members 2 and 45 3 and a removable end member 4 which may be attached to the ends of the side members by means of screws 5. Journalled in the end members is a crank shaft 6 which terminates at one end in a crank 7 or other means for 50 causing the rotation of said shaft. Within the main frame are four box frames 8 identical in construction but arranged in two oppositely disposed pairs. At one side of each frame is a vertical post 9 which carries the sleeve 10 held in place by the set 55 screw 11. Each sleeve has projecting there-

from a threaded stud 12 adapted to pass through one of the slots 13 in the side members of the main frame. The nuts 14 and 15 mounted on each stud provide for rigidly clamping the box frame 8 to the main frame. This arrangement provides for adjustment of the box frame within the main frame in the direction of the slots 13, in a direction perpendicular to the side members 60 of the main frame, and along the vertical posts. In the upper portion of each of the box frames is a pair of oppositely disposed slots or guides 16 in which are received the ends of the bar 17 carrying the free end 65 of a flat flexible ribbon or spring-like member 18, the lower end of which is secured to a bar 19 carried by a bracket 20, which is provided with an externally threaded stud 21 passing through the vertical slot 22 70 in the box frame. Nuts 23 and 24 provide for the adjustment of this bracket both vertically in line with the slot and also in a direction perpendicular thereto along the axis of the stud. To the central portion 75 of the flexible member 18 are secured a pair of bearing members 25 in which is journalled a transverse pin 26. To this pin is secured one end of a connecting rod comprising the end portions 27 and 28 connected by a turn 80 bolt 29, by means of which the portions 27 and 28 may be brought nearer together or forced farther apart in order to provide for adjustment. The end member 28 of the connecting rod is rotatably mounted upon 85 one of the offset portions 30 of the crank 6. A back member 31 having a curved face 32 opposite the flexible member 18 is secured to the side of the box frame facing that member by means of pins 33 and 34 and 90 95 the studs 35 entering the slots 16.

When the shaft 6 is rotated, it will cause the connecting rods journalled on the crank portions to reciprocate, thereby causing the flexible member to function. It will be observed that the movement of this member is limited, its base or lower edge being affixed to the stationary bar 19, while the upper end connected to the bar 17 is free to reciprocate only in the plane of the grooves 100 16. Some alteration in the configuration of the member is possible owing to its resiliency, but it will always be controlled by the limitations imposed upon the movement of the free end and the fact that the other end 105 is fixed.

The approximate cycle of operations is

illustrated in Figs. 5 and 6. If we consider the full line position at the left of Fig. 5 to be the initial position when the crank shaft is at the extreme right-hand end of its throw with respect to the particular box member illustrated at the left of Fig. 5, then further rotation of the shaft will cause the movable end 17 of the ribbon to advance along its slots into the position shown in the dotted lines at the left of Fig. 5. This is approximately the position after the shaft has rotated through an angle of 90 degrees. A further rotation of the shaft will result in the upper end of the ribbon advancing to its limiting position, whereupon the ribbon will become somewhat flattened, as indicated in the full lines at the left of Fig. 6, while a still further rotation of the shaft, bringing it to a position 180 degrees removed from its starting point, will change the concave face of the ribbon to a convex surface. This condition is illustrated in dotted lines at the left of Fig. 6, and also in full lines at the right of Fig. 5. The corresponding position of the parts when a further rotation of 90 degrees has occurred is illustrated in the dotted lines to the right of Fig. 5, the flexible member now being retracted away from the fixed member 31. Continued rotation causes the parts to pass through the stages shown in full and dotted lines, respectively, at the right of Fig. 6, until the starting point is reached. The result of this cycle of operations with respect to each of the box members and its associated parts is to produce an action closely allied to that of the parts of a calf's mouth in feeding, the fixed member 31 corresponding to the roof of the mouth and the flexible member 18 to the calf's tongue. The milking action is therefore one which closely approximates the natural operation and which is therefore extremely efficient. Furthermore, all the parts in my improved apparatus are readily adjustable, so that they may accommodate varying conditions, and are also readily removable for purposes of cleansing or repair. There is no likelihood of excessive wear and there is a minimum of moving parts. The absence of rubber or other non-metallic hygroscopic or absorbent fabric is a further advantage.

In the alternative form of construction shown partially in section in Figs. 7 and 8, the flexible ribbon or spring-like compression member 18 is shown with the bearing members 25, in which is journaled the transverse pin 26. To this pin is secured one end of the connecting rod, as before, save that instead of the form of end portion previously illustrated, there is employed a cylindrical member 36 having the piston 40 therein. The stem 39 of the piston is screw-threaded, engaging the nut 37 having an oppositely threaded stem 38, so that the nut

40 provides for the adjustment of the piston in the manner of a turn buckle. The function of this construction is to introduce a time element in the operation of the compression member, whose retraction does not begin until the head of the piston 40 has traveled the length of its cylinder, as illustrated in Fig. 8. The delay thus secured permits the compression element 18 to remain in engagement with the teat for a longer time, with only the lighter pressure due to the resiliency of the spring member 18, as in practice will sometimes be found desirable.

The arrangement of the four milking units in their common casing and of the crank-shaft with relation to them is such as to admit of the ready application of the device beneath the udder, by inserting one pair of teats in the units at one side, as shown to the left of Fig. 1, whereupon the crank is turned a half revolution, withdrawing the compression members in the other pair of units and permitting the insertion of the other pair of teats.

While I have illustrated and described only one specific embodiment of my device, I appreciate that it is susceptible of wide application, and I do not desire to be limited to the precise structure shown and described.

Having thus described my invention, I claim:

1. In a milking machine, a movable teat-engaging member comprising a thin flexible element, one portion of which is fixed, and means for imparting a reciprocating undulatory motion to said member.

2. In a milking machine, a movable teat-engaging member comprising a thin flexible element, one portion of which is fixed, means for limiting the motion of another portion to a predetermined path, and means for imparting a reciprocating motion to an intermediate portion of said movable member.

3. In a milking machine, a movable teat-engaging member comprising a thin flexible element, one portion of which is fixed, means for limiting the motion of another portion to a rectilinear path, and means for imparting a reciprocating motion to another portion of said movable member.

4. In a milking machine, a movable teat-engaging member comprising a thin flexible element, one end of said element being fixed, means for limiting the motion of the other end to a predetermined path, and means for imparting a reciprocating motion to an intermediate portion of said movable member.

5. In a milking machine, a movable teat-engaging member comprising a thin flexible element, one end of said element being fixed, means for limiting the motion of the other end to a rectilinear path, and means

for imparting a reciprocating motion to an intermediate portion of said movable member.

6. In a milking machine, a movable teat-engaging member comprising a thin flexible metallic ribbon, and means for imparting a reciprocating undulatory motion to said ribbon.

7. In a milking machine, a movable teat-engaging member comprising a thin flexible metallic ribbon having one end fixed, and means for imparting a reciprocating undulatory motion to the free portion of said member.

15 8. In a milking machine, a movable teat-engaging member comprising a thin flexible metallic ribbon, one end of which is fixed, means for limiting the motion of the other end to a predetermined path, and means for imparting a reciprocating motion to an intermediate portion of said member.

9. In a milking machine, a movable teat-engaging member comprising a thin flexible metallic ribbon, one end of which is fixed, means for limiting the motion of the other end to a rectilinear path, and means for imparting a reciprocating motion to an intermediate portion of said member.

10. In a milking machine, a fixed member, a movable teat-engaging member comprising a thin flexible metallic ribbon having one end fixed, means for limiting the motion of the other end of said ribbon to a direction substantially perpendicular to the adjacent surface of said fixed member, and means for imparting a reciprocating motion to an intermediate portion of said ribbon.

11. In a milking machine, a movable teat-engaging member comprising a flexible element and means for imparting to the central portion of said element an undulatory mo-

tion having a reversal of curvature at each cycle.

12. In a milking machine, a movable teat-engaging member comprising a thin flexible ribbon having one end fixed, means for limiting another portion to a predetermined path, means for imparting a reciprocating motion to a portion of said ribbon, and means for altering the initial position of the fixed portion of said member.

13. In a milking machine, a rectangular frame, a plurality of individual milking units arranged in oppositely disposed pairs and adjustably mounted upon said frame, and an actuating shaft centrally disposed with reference to said units and carried by said frame.

14. In a milking machine, a rectangular frame, a plurality of individual milking units arranged in oppositely disposed pairs and adjustably mounted upon said frame, a crank shaft centrally mounted with respect to said individual units and journaled in said frame, and a connecting rod leading from said crank shaft to each of said individual units for actuating the same.

15. In a milking machine, a rectangular frame, a plurality of individual milking units arranged in oppositely disposed pairs and adjustably mounted upon said frame, a crank shaft centrally mounted with respect to said individual units and journaled in said frame, and a connecting rod of adjustable length leading from said crank shaft to each of said individual units for actuating the same.
